UNITED STATES PATENT OFFICE.

FRED J. S. MIELY, OF GENTRY, ARKANSAS.

BULL BOARD FOR CATTLE CARS.

Application filed May 28, 1924. Serial No. 716,458.

To all whom it may concern:

Be it known that I, FRED J. S. MIELY, a citizen of the United States, residing at Gentry, in the county of Benton and State of 5 Arkansas, have invented a new and useful Bull Board for Cattle Cars, of which the following is a specification.

This invention relates to cattle cars and aims to provide a novel form of bull board 10 employed as a guard for guarding the doorway of a car.

An important object of the invention is to provide means for automatically locking the bull board in its active position against animals releasing the same.

A still further object of the invention is the provision of a locking means which may be readily and easily thrown to its inactive position should it be desired to swing the 20 bull board to a position out of use.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a car door and disclosing the bull board as in its active position.

Figure 2 is a sectional view taken on line 2—2 of Figure 1.

Figure 3 is an elevational view disclosing the bull board in its inactive position.

Figure 4 is a sectional view taken on line 40 4—4 of Figure 2.

Figure 5 is a sectional view through the hinge member.

Figure 6 is a perspective view of the pivoted locking element.

Figure 7 is an elevational view disclosing the hinge for the bull board.

Figure 8 is a sectional view taken on line 8—8 of Figure 7.

Figure 9 is a sectional view taken on line 50 9—9 of Figure 3.

Figure 10 is a perspective view of one of the hinge elements.

Figure 11 is a perspective view of the co-operating hinge element.

Figure 12 is an elevational view of the hinge illustrating the locking feature.

Figure 13 is a perspective view of the stop member.

Referring to the drawings in detail, the reference character 5 designates a post at one 60 end of the door opening of the car, to which the hinge of the bull board is secured.

At the opposite side of the door opening is a post 6 which is formed with a cut out portion providing a keeper for the free end of 65 the bull board 7. The reference character 8 indicates a stationary hinge element which is formed with a cut out portion defining ears 10 which are connected by means of the pin 11 which pin provides a support for the 70 locking section 12 of the hinge, permitting swinging movement between the hinge sections.

As shown by Figure 11 of the drawings, the lower ear of the hinge element 8 is 75 formed with a cut out portion 13 adapted to cooperate with the inclined surface 14 of the hinge element 12 to lock the members 8 and 12 against movement with respect to each other, the locking being accomplished 80 by the hinge element 12, and more particularly the inclined surface 14 thereof falling down behind the shoulder 15 defined by the cut out portion 13.

The hinged end of the bull board 7 is 85 provided with an elongated opening 16 that accommodates the eye bolt 17 provided with a head 18 at one end thereof, which head prevents the eye bolt from being drawn 90 through the opening 16.

The eye 19 of the eye bolt accommodates that portion of the hinged section 12 between the opening 20 and free edge of the hinge element 12 to pivotally connect the hinge element 12 and bull board, allowing the bull 95 board to move outwardly to a position as shown by Figure 9, whereupon the bull board may be swung upwardly to its inactive position and supported in such active position by locking means to be hereinafter 100 more fully described.

Disposed adjacent to the elongated opening 16 and secured to the bull board is a stop member 21 which is also provided with an elongated opening 22 adapted to register with the elongated opening 16 providing a wear plate for the eye bolt. At one end of the member 21 is a hook 23 adapted to engage the pin 11 to restrict movement of the bull board and relieve the hinge members 8 and 12, of undue strain caused by 110 cattle rubbing against the bull board.

Located at the free end of the bull board 7 is an upwardly extended lug 24 adapted to be engaged by the pivoted latch member 25 to hold the bull board 7 against movement, until the latch member has been manually operated to disengage the lug 24.

In order that the free end of the bull board 7 may be guided to its keeper, a roller 26 is provided and supported between the 10 side walls of the keeper forming a rest for the free end of the bull board when in its active position.

From the foregoing it will be obvious that when the bull board is in its locked position 15 as shown by Figure 1 of the drawings, it is necessary to lift the hinged end of the bull board to disengage the shoulders defined by the cut out portions 13 and 14, and in order to prevent such upward movement 20 the pivoted latch 27 is provided and arranged above the section 12 as clearly shown by Figure 7 of the drawings, the section 12 being provided with a cut out portion to accommodate the latch member 25 27.

Above the hinge member 8 and at a point adjacent to the upper portion of the door opening is arranged a keeper 29 which is normally closed by the weighted latch member 30 30 which is formed with a camming surface to allow the bull board to enter the keeper when the bull board is moved to its active position to cover the weighted latch member falling to a position to close 35 the keeper 29 and hold the bull board against movement.

If it is desired to release the bull board to permit it to be swung to its inactive position, it is only necessary to swing the latch 40 member 27 to a position out of engagement with the bull board 7 whereupon the hinged end of the bull board may be lifted and

swung rearwardly, the free end of the bull board moving from a position within its keeper, whereupon it may be swung upwardly within the keeper 29. 45

I claim:—

1. A bull board securing device including a hinge member, said hinge member comprising pivoted sections, one of the sections 50 having a shoulder, a bull board secured to the opposite section, the section carrying the bull board adapted to move downwardly to engage behind the shoulder to restrict movement of the bull board, means for connecting the bull board to the hinge to permit sliding movement of the bull board with respect to the hinge, when the section of the hinge to which the bull board is secured is moved vertically, and means disposed above the section of the hinge carrying the bull board for preventing vertical movement of one section of the hinge with respect to the other. 55

2. A bull board securing device including a hinge member, comprising sections, a bull board secured to one of the sections and mounted for sliding movement when the section of the hinge carrying the bull board is moved vertically, a shoulder on one of 70 the hinge sections for engaging the opposite hinge section to prevent swinging movement of the bull board, carried by the hinge, and a latch member pivotally mounted above the bull board and adapted to engage one 75 of the hinge sections for restricting vertical movement thereof.

In testimony that I claim the foregoing as my own, I have hereto affixed my signature in the presence of two witnesses.

FRED J. S. MIELY.
